SHIPPING TAG

Raymond E. Fleming, Philadelphia, Pa., assignor
to National Fiberstok Envelope Co., Philadelphia, Pa., a corporation of Pennsylvania

Application May 11, 1939, Serial No. 272,959

4 Claims. (Cl. 40—21)

This invention has to do with shipping tags and is concerned primarily with a novel arrangement for anchoring a wire tie to a tag.

Ordinarily, shipping tags are formed with an eyelet, the edges of which are usually reinforced by patches. It has been the conventional practice to employ a wire tie element in securing the tag to an article and this wire tie has been affixed to the tag by passing the same through the eyelet and twisting the two single strands of the wire together above the edge of the tag.

This practice has been followed whether the main body portion of the tie is a single or double strand and certain disadvantages attach to this now prevalent method, which are intended to be remedied by this invention. In the first place, the single strand of wire passing through the eyelet presents a fairly sharp surface which has a tendency to cut the edge of the opening even though the latter is reinforced by the patches. This tendency has been so noticeably felt in many instances that frequently the patches have been further reinforced by metallic grommets. There is also a tendency for the single strand of wire to cut or score the upper edge of the tag above the eyelet.

When two single strands of wire are twisted together tightly so as to effect the required secure connection, the wire is bent over a comparatively small twisting arc, thus forming sharp turns in the wire. These sharp turns weaken the wire ties and, in many instances, the ties are broken off at the twisting zone.

Another noticeable disadvantage attending the use of the known practice above described is that there is no suitable anchorage to which the upper end of the tie may be secured after being passed around the article to which the tag is to be attached. If the wire is twisted back on itself, the same undesirable feature, as to sharp turns in the wire, above-noted, occurs. Furthermore, if the free end of the wire is passed through the eyelet, the likelihood of the latter becoming scored or cut by the wire is further increased.

With the foregoing conditions in mind, this invention has in view, as its foremost objective, the provision of a shipping tag including an eyelet to which a wire tie element is attached by a novel arrangement, eliminating the outlined difficulties.

More in detail, the invention has in view, as an object, the provision of a shipping tag formed with an eyelet into which a wire tie element is secured by first folding the wire tie element back on itself to provide a double strand of wire ter-

minating in a bight. The bight is passed through the eyelet and the double strand immediately succeeding the bight is twisted about the double strand of the wire tie. With this arrangement the twisting arc for the wire is longer, as the double strand presents a greater thickness. Furthermore, in lieu of the single strand that provides a cutting edge in the eyelet, two strands closely adjacent one another are provided, which have an appreciable breadth to materially decrease, if not entirely eliminate, this hazard.

Another important advantage of the invention is that the bight at the end of the double strand affords a loop that may be employed as an anchor for the free end of the tie element.

If the main body portion of the wire tie is to be a single strand, the double strand structure is continued back only sufficiently far to effect the connection with the tag, above-noted. However, the invention is equally susceptible of use with the twin strand type of tie, in that a single length of wire may be doubled back on itself, with the bight formed substantially in the middle thereof, the bight is then passed through the eyelet in the manner above-described and twisted back on the double strand above the tag edge, leaving twin strands of wire that are available for affixing to the article or package.

Various other more detailed objects and advantages of the invention will in part become apparent and in part be hereinafter stated as the description of the invention proceeds.

The invention, therefore, comprises a shipping tag including a wire tie element that is formed with a bight providing a double strand structure of the tie of sufficient length to permit the bight to be passed through the eyelet in the tag and twisted back over a double strand of the wire, leaving the bight available as an anchoring loop.

For a full and more complete understanding of the invention, reference may be had to the following description and accompanying drawing, wherein:

Figure 1 is a view in side elevation showing the improved wire tie element of this invention after it is passed through the eyelet and prior to twisting.

Figure 2 is a view taken normal to the showing of Figure 1, developing the arrangement after the twisting has been completed.

Figure 3 is a side view similar to Figure 1, showing the free end of the tie anchored in the bight, and

Figure 4 is a fragmentary view of the tag including the twin strand tie element.

Referring now to the drawing, wherein like reference characters denote corresponding parts, an ordinary shipping tag is shown at T as being made from any suitable material, and of any desired shape. The shape of these tags have assumed the more or less conventional form illustrated, and, as a general rule, they are made from a cardboard or tough paper material.

It will be noted that the corners of the tag 10 T are cut off at one end, as shown at 10, and adjacent this end of the tag T the latter is formed with an opening 11, defining the eyelet of the tag. The opening 11 is preferably reinforced by patches 12, a patch being secured to 15 the tag T on each face by the use of a suitable adhesive.

Figures 1, 2 and 3 develop a showing of the single strand type of wire tie. First referring to Figure 1, it is noted that a strand of wire 13 is doubled back on itself a required length, the doubled back portion being designated 14, to define a bight 15. This bight 15 is passed through the eyelet 11, as depicted in Figure 1. After the eyelet has been passed through the opening, the 25 double strand structure is continued back above the upper edge of the tag T to provide two double strand structures which are available for twisting about one another.

Figure 2 shows the arrangement after the twisting 30 has been effected, and it is particularly notable that the double strand structure provides a comparatively long twisting arc in the wire which eliminates unduly sharp turns or bends in the wire, which would tend to weaken the same. The 35 twisting is identified by the reference character 16, and it will be carried out in such a manner as to leave the bight 15 free as an anchoring means.

The free end of the wire tie 13, which is designated 40 17, is then passed around the article or package to which the tag is to be secured, after which it is passed through the bight 15 in the manner shown in Figure 3. The single strand may be twisted back on itself to complete the anchorage, as illustrated.

Figure 4 shows a modification in that the single 45 strand tie 13 is replaced by a twin tie designated 18. The actual structural connection of the twin strand 18 to the tag T is the same as that above described. The only material difference in effecting the connection is in the relative location of the bight 15.

In the form of the invention shown in Figures 1, 2 and 3, the bight 15 is not formed at the center of the length of wire, but more closely 55 adjacent one end thereof. When the twin strand of Figure 4 is to be employed, the bight 15 is formed substantially in the middle of the length of wire, providing a tie element that is of a dou-

ble strand throughout its entire length. After formation of this double strand arrangement, the bight 15 is passed through the eyelet and twisted back upon itself in the manner above described, and the bight 15 may also be employed as an 5 anchorage in a manner above described.

While preferred specific embodiments of the invention are hereinbefore set forth, it is to be clearly understood that the invention is not to be limited to the exact constructions illustrated 10 and described, because various modifications of these details may be provided in putting the invention into practice, within the purview of the appended claims.

I claim:

1. A shipping tag of the character described comprising a tag member formed with an eyelet, and a wire tie element having a considerable length extending free of the tag and adapted to encircle an article, said tie element being attached 20 to the tag member by a connection consisting of a double strand structure defined by forming a bight in the wire tie, said double strand structure being twisted back on itself leaving the bight available as an anchoring loop substantially at 25 said twist, said anchoring loop being adapted to be engaged by the free end of said tie element after an article has been encircled thereby.

2. A shipping tag of the character described comprising a tag member formed with an eyelet, 30 a single strand wire tie element having a bight formed adjacent one end providing a double strand structure at that end, the said double strand structure passing through the eyelet and being twisted back upon itself, with said bight 35 disposed substantially at the twisted portions.

3. A shipping tag of the character described comprising a tag member formed with an eyelet, a twin strand wire tie element consisting of a length of wire having a bight formed substantially 40 in the middle of said length, the end of the twin strand tie element that carries said bight being passed through the eyelet and twisted back on a portion of said twin strand adjacent to said tag member, with said bight substantially at said 45 twist, and twin strand portions included in said length of wire and adapted to encircle an article.

4. A shipping tag of the character described comprising a tag member carrying an attaching eyelet, a wire tie element having one end free for 50 encircling an article and its other end attached to said tag member through said eyelet, said attached end comprising plural strands of wire joined by a bight located in close proximity to said attached end with said plural strands looped through said eyelet and being twisted together to 55 hold said tag.

RAYMOND E. FLEMING.
